UNITED STATES PATENT OFFICE.

EDWARD PETER POULSEN, OF MENDHAM, NEW JERSEY.

MOP WRINGER.

Application filed July 25, 1922. Serial No. 577,289.

To all whom it may concern:

Be it known that I, EDWARD P. POULSEN, a subject of the King of Denmark, and a resident of Mendham, in the county of Morris and State of New Jersey, have invented a new and Improved Mop Wringer, of which the following is a full, clear, and exact description.

This invention relates to devices for wringing mops and has particular reference to a mop wringer which is designed to be associated with a bucket or pail for removing from a mop the majority of the water and discharging the same into the pail or bucket.

One of the principal objects of the present invention is to provide a mop wringer of extremely simple construction which renders the same inexpensive to manufacture and produce.

As a further object the invention contemplates a mop wringer which may be expeditiously associated with or removed from a bucket or pail.

The invention further contemplates a mop wringer which is adjustable whereby the same will operate in connection with buckets or pails of various height.

With the above recited and other objects in view, the invention resides in the novel construction set forth in the following specification, particularly pointed out in the appended claims and illustrated in the accompanying drawing, it being understood that the right is reserved to embodiments other than those actually illustrated herein to the full extent indicated by the general meaning of the terms in which the claims are expressed.

In the drawing—

Figure 1 is a perspective view illustrating the mop wringer in applied position to a bucket or pail.

Fig. 2 is a fragmentary sectional plan view therethrough taken approximately on the line 2—2 of Fig. 1, and illustrating the mop engaging elements respectively in full and dotted lines and in open and closed position.

Referring to the drawing by characters of reference, 10 designates a plate which is formed at its upper end with an inturned flange 11 designed to fit over the upper edge of a bucket or pail. The plate 10 is further provided with outwardly projecting parallel side flanges 12 having ver-

tically aligned apertures 13 within which the outturned extremity 14 provided at the upper end of a U-shaped frame 15 are engageable. The lower end of the U-shaped frame 15 is turned outwardly at an angle to provide a foot engaging portion 16 upon which the foot of the user is placed when the wringer is in use. The apertures 13 permit of the vertical adjustments of the upper end of the frame 15 with respect to the plate 10 whereby the device may be adjusted to buckets or pails of various height. The inturned flange 11 at the upper end of the plate 10 has connected thereto for universal turning and swinging movements a pair of rollers 17 which are provided at their outer ends with independently rotatable handles 18. The universal connection between the members 17 and the flange 11 consists of axially projecting pins 19 anchored in the rollers 17 and extending through apertures 20 in the flange, the outer ends of said pins being headed as at 21 to prevent detachment of the rollers from the flange 11.

In use and operation of the device after the frame 15 has been properly adjusted with respect to the plate 10 to approximately conform to the height of the pail or bucket, the flange 11 is engaged over the upper end of the bucket or pail. In wringing the mop, the user places the foot on the foot engaging portion 16 and inserts the mop between the rollers 17 after the same have been separated as illustrated in dotted lines in Fig. 2. The rollers are then advanced toward each other and the handles 18 grasped in the hand to prevent relative separation of the outer free ends of the rollers. The mop is then drawn through the rollers which will rotate and at the same time squeeze the water from the mop allowing the same to be discharged into the bucket. The simplicity of the construction, as well as the use and operation is apparent and it thus follows that an extremely simple and inexpensive mop wringer has been provided which may be manufactured and sold at a minimum cost to the consumer.

I claim:

1. A mop wringer including a pair of mop engaging elements arranged side by side, means adapted to embrace the upper edge of a bucket, a connection between one end of each mop engaging element and the portion of the bucket edge embracing means

disposed at the inner side of the bucket for permitting universal turning and swinging movements of said mop engaging elements, and a foot engaging element depending from said means and connected thereto for respectively holding said means in embracing engagement with the upper edge of the bucket and for preventing accidental turning movement of the bucket, said foot engaging element having adjustable connection with the bucket embracing means.

2. A mop wringer comprising a plate having an inwardly and downwardly turned flange at its upper end engageable over the upper edge of a bucket, parallel side flanges on said plate having vertically spaced aligned apertures, a foot engaging element comprising a U-shaped frame having outturned upper extremities engageable within the apertures of the side flanges, said frame having an outturned lower foot engaging portion, a pair of rollers each having a connection at one end with the inwardly and downwardly turned flange to permit of universal swinging and turning movements of said rollers with respect to said plate.

3. A mop wringer comprising a plate having an inwardly and downwardly turned flange at its upper end engageable over the upper edge of a bucket, parallel side flanges on said plate having vertically spaced aligned apertures, a foot engaging element comprising a U-shaped frame having outturned upper extremities engageable within

the apertures of the side flanges, said frame having an outturned lower foot engaging portion, a pair of rollers each having a connection at one end with the inwardly and downwardly turned flange to permit of universal swinging and turning movements of said rollers with respect to said plate, said universal connection consisting of axially projecting pins anchored within said rollers and extending through the flange, and heads formed at the outer end of said pins.

4. A mop wringer comprising a plate having an inwardly and downwardly turned flange at its upper end engageable over the upper edge of a bucket, parallel side flanges on said plate having vertically spaced aligned apertures, a foot engaging element comprising a U-shaped frame having outturned upper extremities engageable within the apertures of the side flanges, said frame having an outturned lower foot engaging portion, a pair of rollers each having a connection at one end with the inwardly and downwardly turned flange to permit of universal swinging and turning movements of said rollers with respect to said plate, said universal connection consisting of axially projecting pins anchored within said rollers and extending through the flange, and heads formed at the outer end of said pins, the said rollers having swiveled handles at their outer ends independently rotatable with respect to the rollers.

EDWARD PETER POULSEN.
